UNITED STATES PATENT OFFICE

RASMUS M. HVID, OF CHICAGO, ILLINOIS

COMPRESSOR CONSTRUCTION FOR ICE MACHINES

Application filed October 25, 1927. Serial No. 228,513.

My invention relates to ice machines, and particularly to a detail of construction of the machine disclosed in my copending application, Serial No. 228,510, filed of even date herewith.

An object of my invention is to provide an efficient driving means for the compressor and oil pump and to suitably seal the high pressure chamber without the use of a stuffing box or packing gland of the common sort. One of the fundamental difficulties in the design and operation of ice machines of the present type is that of sealing the high pressure gas and oil. Stuffing boxes are uncertain and likely to deteriorate following continued use, and my improvement is intended to eliminate such expedients. To accomplish the desired result, I provide a ground metal-to-metal sealing joint, and in order to insure continued and effective operation, I have divided the drive shaft into three sections, connecting them by a loose coupling in order to avoid any possibility of uneven wear or distortion of the sealing point.

Another improvement herein disclosed relates to the means for separating gas and oil and thereby preventing the accumulation of oil in the expansion coils. The desired result is secured by providing a conical disc within the high pressure chamber, extending across the space between the compressors, oil pump and the outlet to the condenser.

The invention will be more readily understood by reference to the accompanying drawings in which:

Fig. 1 is a vertical sectional view through an ice machine constructed in accordance with my invention, and

Fig. 2 is a detailed sectional view showing the sealing device employed in the machine.

The machine of my invention comprises a three-part casing, 10, 11, 12, the space within the casing being under high pressure. The intermediate portion 11 acts as a support for a compressor, 13, and a bearing for a driven

shaft, 14. An oil pump, 15 is mounted within the lower portion of the high pressure chamber, the pump having a discharge pipe, 16 for delivering gas and oil through the intermediate wall, 11, into the upper portion of the high pressure chamber. The compressors and oil pump are driven by the shaft 14. Connected to the upper portion of the driven shaft 14 is a conical disc 17 having a marginal flange 18 which lies close to an annular projection 19 from the wall 10. Oil thrown upward by the pump or carried in suspension by the gas in its travel to the outlet pipe, 20, contacts with the rapidly revolving disc 17 and is thrown outward, while the gas passes around the disc, thence upward and outward through the pipe.

A motor, A, is mounted directly above the casing being supported on suitable legs, 21. A motor shaft 22 is operatively connected to the motor and an intermediate shaft 23 joins the motor shaft 22 and the driven shaft, 14. A loose coupling 24, of common form, operatively connects the shafts 22, 23, while a similar loose coupling connects the shafts 23, 14. The shaft 23 has an enlarged cylindrical portion 25 provided with a central opening and with a transverse slot, 26, in its lower end. A washer 27, has a central, transverse lug 28, and oppositely disposed, laterally projecting lugs 29. The lug 28 engages in the slot in the enlarged portion 25, while the lugs 29 engage the slots in a clamping nut, 30, having threaded engagement with the shaft 14 and serving to hold the oil separating disc in place.

At the junction of the small and large portions of the shaft, 23, I provide a tapered seat, 31 which cooperates with the ground surface on a plug, 32, composed of special alloy, and fitted within the bearing member 33, removably fixed to the top wall of the casing, 10. The provision of the enlarged portion of the shaft insures a constant and firm

seat of the ground surfaces, due to the pressure within the high pressure chamber.

However, in order to insure constant seating at all times, regardless of the presence of increased pressure within the chamber, I provide a compression spring, 34 within the recess in the enlarged portion of the shaft, the spring bearing against the lug, 28 and tending to separate the shafts, 14, 23.

By so constructing the shafts that the intermediate shaft which projects through the wall is entirely independent of the other two shafts, I am able to insure long and efficient operation without the possibility of distortion or uneven wear because of inaccuracies in construction or assembly.

The machine operates as follows: The motor being in operation, the shaft is rotated causing reciprocation of the piston in the cylinder 13. Gas is drawn into the compressor from the expansion chamber (not shown) through the pipe 35 and check valve 36. During the compression stroke of the piston, the cylinder has rotated so that the ports 37 are closed and the compressed gas is discharged past the flexible valve 38 at the end of the cylinder into the chamber between the walls 11 and 12 within which the compressor is located. The compressed gas passes upwardly through the pipe 16 into the upper chamber and thence through the pipe 20 into the condenser (not shown). From the condenser the liquid passes to the low side through the pipe 39.

The drive shaft 14 also operates the oil pump, and as oil is discharged upwardly through the pipe 16, the compressed gas travels with it. An important reason for the oil separating disc 17 is that the compressed gas has no other escape from the lower chamber except through the pipe 16 with the oil, resulting in a mixture of oil and gas. Thus to prevent carrying over of oil into the coils the separator is utilized. The oil received in the upper chamber passes through the opening 40 into the space around the shaft 14 and from there it returns to the lower chamber.

Numerous changes and modifications may be made in the construction shown, and I do not wish to be limited except as indicated in the appended claims.

I claim:

1. In a compressor for ice machines having a high pressure chamber and a motor mounted outside and entirely exteriorly thereof, the combination of a drive shaft connected to the motor, an intermediate shaft projecting through a wall of the high pressure chamber, a driven shaft located entirely within the chamber, and loose couplings between the three shafts.

2. In a compressor for ice machines having a high pressure chamber and a motor mounted outside and entirely exteriorly thereof, the

combination of a drive shaft connected to the motor, an intermediate shaft projecting through a wall of the high pressure chamber, means on said intermediate shaft providing a seal, a driven shaft located entirely within the chamber, and loose couplings between the three shafts. 70

3. In a compressor for ice machines having a high pressure chamber and a motor mounted outside and entirely exteriorly thereof, the combination of a drive shaft connected to the motor, an intermediate shaft projecting through a wall of the high pressure chamber, means actuated by the pressure within said chamber for effecting a sealing engagement between the shaft and its bearing, a driven shaft located entirely within the chamber, and loose couplings between the three shafts. 75

4. In a compressor for ice machines having a high pressure chamber and a motor mounted vertically above the same, the combination of a motor shaft, an intermediate shaft projecting through a wall of said chamber, and a driven shaft entirely within said chamber, loose couplings connecting the three shafts, and means on said intermediate shaft providing a tapered ground bearing seat. 80

5. In a compressor for ice machines having a high pressure chamber and a motor mounted vertically above the same, the combination of a motor shaft, an intermediate shaft projecting through a wall of said chamber, and a driven shaft entirely within said chamber, loose couplings connecting the three shafts, said intermediate shaft having one portion of small diameter and another portion of large diameter and a tapered seat provided at the junction of said large and small diameters. 95

6. In a compressor for ice machines, the combination of a motor having a shaft, means providing a high pressure chamber, a driven shaft located entirely within said chamber, a connecting shaft between the motor and driven shafts, said connecting shaft projecting through a wall of said high pressure chamber, a bearing plug mounted in said wall and means on said plug and said connecting shaft for providing a tapered ground seat. 105

7. In a compressor for ice machines, the combination of means providing a high pressure chamber, a compressor and an oil pump within said chamber, means for delivering compressed gas through said oil pump, and an oil separator located in the upper portion of said high pressure chamber and adapted to separate the gas and oil. 115

8. In combination, walls providing upper and lower high pressure chambers, a compressor and an oil pump in the lower chamber, means for delivering high pressure gas from the lower to the upper chambers through said oil pump, and a revoluble disc 125

130

in the upper chamber adapted to separate the oil and the gas.

9. In a compressor for the ice machine, the combination of walls providing a high pressure chamber, a motor driven shaft within said chamber, means for compressing gas and means for circulating oil and a disc secured to said shaft and rotating therewith, said disc projecting across the space in the chamber between the compressor and outlet from the high pressure chamber, and adapted to separate oil from the gas.

In testimony whereof I have affixed my signature.
